United States Patent Office

Des. 217,729
Patented June 2, 1970

217,729

CLOCK HOUSING

Lawrence H. Wilson, Grosse Pointe, Mich., assignor to
Sunbeam Corporation, Chicago, Ill., a corporation of
Illinois

Filed June 3, 1969, Ser. No. 17,496

Term of patent 14 years

Int. Cl. D10—01

U.S. Cl. D42—7

FIG. 1 is a front elevational view of a clock showing my new design;

FIG. 2 is a side elevational view thereof;

FIG. 3 is a sectional view thereof taken along the section line 3—3 of FIG. 1.

I claim:

The ornamental design for a clock housing, as shown.
